US0D1025979S

(12) United States Design Patent (10) Patent No.: US D1,025,979 S
(45) Date of Patent:  May 7, 2024

(54) INFORMATION HANDLING SYSTEM

(71) Applicant: Dell Products L.P., Round Rock, TX (US)

(72) Inventors: Iven Dieterle, Taipei (TW); Ian Li, Taipei (TW); Jihun Yeom, New Taipei (TW); Hsuan-Ping Weng, Taipei (TW); Yu-Hsuan Chiu, Caotun Township (TW)

(73) Assignee: Dell Products L.P., Round Rock, TX (US)

() Term: 15 Years

(21) Appl. No.: 29/842,562

(22) Filed: Jun. 14, 2022

(51) LOC (14) Cl. 14-02

(52) U.S. Cl.

USPC D14/315

(58) Field of Classification Search

USPC D14/315-327, 341, 345, 439-440; D18/1-3.1, 4.1-4.6, 12.1-12.3; D21/324, D21/329-330, 332, 515

CPC G06F 1/1616; G06F 1/1633; G06F 1/1656

(57) CLAIM

We claim the ornamental design for an information handling system, as shown and described.

DESCRIPTION

FIG. 1 is a front perspective view of the information handling system comprising the present invention;

FIG. 2 is a front elevation view thereof;

FIG. 3 is a rear elevation view thereof;

FIG. 4 is a right side view thereof;

FIG. 5 is a left side view thereof;

FIG. 6 is a top view thereof;

FIG. 7 is a bottom view thereof;

FIG. 8 is a bottom perspective view thereof; and,

FIG. 9 is a front perspective view of the information handling system in an open position.

Broken lines shown in the drawings illustrate portions of the information handling system and form no part of the claimed design.
